UNITED STATES PATENT OFFICE.

ALBERT R. LONG, OF BALLSTON, VIRGINIA.

ROTARY INTERNAL-COMBUSTION ENGINE.

1,408,753.

Specification of Letters Patent. Patented Mar. 7, 1922.

Application filed January 8, 1920. Serial No. 350,099.

To all whom it may concern:

Be it known that I, ALBERT R. LONG, a citizen of the United States of America, residing at Ballston, in the county of Alexandria and State of Virginia, have invented certain new and useful Improvements in Rotary Internal-Combustion Engines, of which the following is a specification.

This invention relates to improvements in rotary internal combustion engines such as described and claimed in my co-pending parent U. S. application Serial No. 350,098, filed January 8, 1920; and the invention relates more particularly to the provision of a blower device for rotary internal combustion engines of the two-cycle type whereby a uniform draft of sufficient velocity will be supplied to the engine cylinders for purging the same of burnt gases whereby to perfect combustion and also to cool said cylinders in order that efficient functioning of the engine will be ensured.

It is also an object of my invention to provide a blower device which by reason of the arrangement of air intake ports in the engine cylinders will furnish the greatest amount of air possible to said cylinders.

Other objects will be in part obvious, and in part pointed out hereinafter.

In order that the invention and the manner of its application may be readily understood by persons skilled in the art, I have in the accompanying illustrative drawings and in the detailed following description based thereon set forth one embodiment of the invention.

In these drawings:

Figure 1 is a vertical longitudinal section through a rotary cylinder engine with the improved blower applied;

Figure 2 is a section taken at right angles to Figure 1, on the line 2—2 thereof looking in the direction in which the arrows point;

Figure 3 is a similar section taken on the line 3—3 of Figure 1 looking in the direction in which the arrows point, and

Figure 4 is a fragmentary detail illustrating the arrangement of the blower or fan blades.

Having more especial reference to the drawings, in connection with which like reference characters refer to corresponding parts, 1 designates the base of the engine parts, 1 to which a stationary crank-shaft 2 is secured, said crank-shaft being formed with

an extension 2', the purpose of which will be hereinafter described. A circular bearing 3 is arranged upon the base concentric of the crank-shaft and rotatably supports 60 the crank-case 4 and the radially disposed cylinders 5 of the engine, which have pistons 6 of the sleeve valve type working therein and connected to the crank-shaft to permit of rotation thereabout. Suitable fuel intake and exhaust ports are formed in the several cylinders, the intake ports being controlled by properly timed valves 7 of the piston type, working in valve cylinders 8 adjacent their respective cylinders while the 70 exhaust ports are controlled by the pistons of their cylinders as set out in the heretofore mentioned copending application. Air intake ports 9 are formed about the inner ends of said cylinders in a manner to afford 75 the greatest possible portage area and are also controlled by the pistons of their respective cylinders; these pistons being formed with circularly disposed ports 10 adapted to align with said air ports upon 80 the finish of the working strokes of the several pistons, at which time, the cylinders exhaust ports are open, thereby allowing a purging current of air to pass from the inner ends of the cylinders, through the same, 85 and then be discharged therefrom with the burnt products of combustion by way of the exhaust ports.

As means for forcing the cooling and purging draft through the engine cylinders, 90 I employ a form of rotary blower comprising an annular casing 11 carried upon the outer sides of the valve cylinders by way of ports 12, while the valve cylinders communicate with their respective engine cylinders 95 through the air intake ports 9. A series of circularly disposed fan blades 13 are carried by the inner sides of the casing. The casing is positioned concentrically of the crank-shaft extension 2' being engaged with a circular bearing 14 similar to the bearing 3 and also supported upon the stationary crank shaft. Positioned in and concentrically of the casing 11 is a hub 15 having its inner and outer ends reduced and provided with 100 bearings 16 adapted to rotatably engage about the extension 2', said hub being secured against displacement with relation to the extension 2' by means of a locking screw 17 turned into with its outer end as shown in 110 the Figure 1. Spaced series of circularly disposed fan blades 18 are carried on the

sides of the hub and are arranged on the opposite sides of the blades 13 on the casing 11. In this connection, it should be noted that the fan blades 13 and 18 are disposed at opposite oblique angles, as illustrated in the Figure 2 in order that they will function to draw air from the atmosphere into the engine when rotated in the manner now to be described.

10 An internal ring gear 19 is supported in the bottom of the casing 11 upon an annular upstanding flange 20 which is disposed in concentric relation to the bearing 14, while a pinion 21 is secured to the lower reduced end of the hub 15 and is adapted to be connected to and driven by said ring gear by means of an idler 22 mounted for rotation upon a bracket 23 immovably secured to the crank-shaft connection 2'. Thus, it will be understood that upon rotation of the ring gear with the casing 11 and the engine cylinders rotary motion in an opposite direction will be stepped to the pinion 21 through the idler 22 and in consequence, the fan blades 13 and 18 will be caused to rotate in opposite directions for drawing air into the engine cylinders.

15 The operation of the engine provided with my invention may be reviewed as follows: With the compression and subsequent firing of the combustion charges in the cylinders, said cylinders will be caused to rotate about the crank-shaft 2. The fan blades 13 and 18 will also be rotated to draw air from the atmosphere. At timed intervals the sleeve valve type pistons 6 will align with the exhaust ports of their respective cylinders and also, the air intake ports in these pistons will align with the air intake ports 9 in said cylinders at which time, a clear way for a cooling and purging draft of air will be provided, said air being supplied from the blower means by way of the port 12, and in passing through the cylinders will thoroughly scavenge or sweep the same clear of all burnt products of combustion in addition to cooling said cylinders in order that the same will be maintained at temperatures

such as will cause efficient operation of the engine. It will be also appreciated that some of the blast of air through the cylinders will remain therein and will mix with the fuel supplied from the fuel supply means for perfecting combustibility.

20 While I have shown my improved blower device applied to a design of engine peculiar to my invention described and claimed in a co-pending application for Letters Patent, it should be well understood that the device can be as advantageously used in connection with other designs of engines, some of which are now prevalent in the art, such as conditions or preference may dictate.

25 It is further manifest that the construction and arrangement of my invention may be subjected to various modifications, and therefore, such modifications as are within the scope of my claim, I consider within the spirit of my invention.

30 What I claim is:

35 In combination with a multiple rotary cylinder engine, an annular upright casing carried by said cylinders adjacent their inner ends and communicable with the interiors of such cylinders, circularly disposed fan blades carried interiorly of the annular casing, an upright extension from the crank shaft of the engine, a hub loosely mounted on said extension and disposed concentrically of the annular casing, other circularly disposed fan blades carried on the peripheral surface of said hub arranged above and below said first fan blades, and means operable upon functioning of the engine for transmitting rotary motion from the casing to said hub in an opposite direction to the rotation of the former, whereby to supply drafts of purging air to the interiors of said cylinders at regular intervals.

40 In testimony whereof I affix my signature in presence of two witnesses.

ALBERT R. LONG.
